UNITED STATES PATENT OFFICE.

WILLIAM GREGORY KETT, OF OAKLAND, CALIFORNIA, ASSIGNOR OF ONE-HALF TO
LUDWICK H. HIESCH, OF SAN FRANCISCO, CALIFORNIA.

BRUSH.

Application filed August 17, 1922. Serial No. 522,347.

To all whom it may concern:

Be it known that I, WILLIAM GREGORY KETT, a citizen of Australia, residing at Oakland, in the county of Alameda and State of California, have invented certain new and useful Improvements in Brushes, of which the following is a specification.

This invention pertains to an improvement in brushes and has particular reference to a means for greatly facilitating the removal of accumulated material in and around the bristles, as well as offering a means of adjusting the lengths of the exposed bristles and thereby adding greatly to the utility thereof.

All brushes, whether having hair, fiber or metallic bristles are more or less difficult to clean and keep clean. In brushes having hair or fiber bristles, much lint, fuzz and matter of various kinds is sure to accumulate down in and between the tufts of bristles.

This accumulation of matter is very difficult of removal by ordinary methods, where each tuft must be independently manipulated, usually with some pointed implement, in order to dislodge the accumulations. Even if a number of tufts can be operated upon simultaneously the cleaning is not as effective as might be desired, and the time required is out of all proportion to the result obtained.

One of our most necessary articles of toilet, the familiar hair brush, is particularly difficult to keep clean and sanitary. The bristles are usually quite fine, and the tufts are set close together, and the aggravating way in which strands of hair and other miscellaneous matter can accumulate in and around the bristles of this most useful device is well known.

Cleaning one of these favorite articles with an old comb is only partially effective and is likely to be somewhat destructive as well. The tufts of bristles are too large to enter the teeth of even a large comb, so they are more or less broken and bent in the operation, and the brush thus cleaned is almost sure to be damaged.

The constant flexing given the bristles of most brushes soon destroys their resilience, and then in order to keep up the effectiveness of the brushing, for whatever purpose,

we invariably increase the pressure, with the result that the bristles are further flexed and bent and soon the brush becomes ineffective, or at least insufficiently effective for our purpose and is discarded.

Where brushes having long stiff bristles, set far enough apart for proper cleaning by ordinary methods, are used constantly for certain purposes they invariably lose their resilience long before they are actually worn out, and have to be abandoned on this account.

The large steel bristle brushes used for cleaning butchers' blocks are very effective for the first cleaning. The bristles are stiff and long and flex sufficiently in action to loosen up the particles of meat and bone adhering to the block and throw them out and away, but are too flexible for final cleaning, for which purpose a short stiff bristle is desired.

My invention described, illustrated and claimed herein, overcomes in a very large degree all of the defects and difficulties enumerated.

A principal object of my invention is to provide means in a brush having tufted bristles, for simultaneously cleaning all of the tufts of any kind of accumulated matter by an easy manipulative method and without injury to the tufts or to individual bristles in the tufts.

Another object is to provide means for regulating the stiffness, or, I might say, resilience of the bristles, thus adapting a brush of given stiffness and resilience to manifold uses.

Other objects and advantages will become apparent by a study of the drawings herewith, wherein I have illustrated one embodiment of my invention in a concrete form. It is to be understood, however, that I do not wish to limit myself to the exact construction shown, but wish to include as my invention all those forms and modifications as will produce the results and advantages inherent in the invention defined in the appended claim.

Reference now being had to the accompanying drawings wherein like figures of reference indicate like parts in the various views.

Figure 1 is a perspective of one of my im-

proved brushes showing the cleaning device in a normal position against the back of the brush and resting at the base of the bristles.

Figure 2 is an end view showing the parts in the same position as Figure 1.

Figure 3 is an end view the same as Figure 2 but with the movable element in the opposite position, showing how it moves along the tufts of bristles in the act of cleaning, 10 or for adjustment to stiffen the bristles for some particular use.

The numeral 1 in the drawings represents the back of the brush, 2 represents the tufts of bristles and 3 represents a member movably secured to the back.

The member 3 represents the essence of my invention and comprises a metallic shield or plate having depending side portions 4, and brace rods 5 across the ends to act as 20 stiffening members as well as stop members.

It will be observed that the plate adjacent the tufts of bristles is perforated as at 6, and that a tuft of bristles extends up through each perforation. The normal 25 movement of the plate 3 is just short of passing beyond the ends of the bristles 2, so that there is no danger of it becoming out of adjustment therewith.

The brush back is recessed at the sides as 30 at 7, and at the ends as at 8. The side recesses carry serrated surfaces having longitudinal lines running therethrough that have a tendency to engage the free edges of the member 3 when it is in adjusted position 35 and gripped by the hand of the operator and thus help to hold the adjustment. The end recesses 8 form paths for the rods 5 to move in and the ledges 9 form stops to prevent the plate 3 from being pulled beyond the 40 ends of the bristles.

In cleaning a brush equipped with this invention it is only necessary for the operator to pull the plate 3 as far forward as it will go, as per Figure 3, when all of the 45 accumulations of hair, lint, fuzz or what not will be pushed to the ends of the bristles where it can easily be removed with the fingers or any suitable implement.

In using the invention for the purpose of 50 stiffening the bristles of a brush that is too

soft or flexible or for stiffening bristles that have lost their resilience through long, or improper use, the plate 3 is moved forward along the bristles until the desired stiffness is obtained, when it may be gripped by the 55 side flanges 4 and firmly held in place while being manipulated, the serrated surfaces engaging the free edges of the member 3 and assisting in holding the adjustment.

Referring again to the butchers' blocks. 60 It appears that the manipulator in cleaning the block likes a stiff but somewhat flexible brush for preliminary cleaning, the stiffness serves to loosen the accumulated material on the surface of the block and the flexibility tends to throw the material out and away from the block. Then for final cleaning he desires a short stiff bristle that will have more of a cutting and scraping action. With my invention he has simply to move 65 the plate member 3 to any position he likes to get any degree of stiffness desired, thus making the one brush serve a dual purpose.

By adjusting the member 3 to the limit of its movement he can get the maximum stiffness for final cleaning, and by adjusting it only slightly forward along the tufts of bristles he can with a nicety adjust the bristles to exactly the resilience he likes for his preliminary work.

Having thus described my invention what I claim as new and desire to secure by Letters Patent of the United States is:—

A brush including a back and a plurality of bristle tufts extending from one face 85 thereof, an apertured plate movable to and from the face of said back and through the apertures of which said tufts project, said plate being bent at opposite sides to overlie the side edges of said back, members uniting 90 the opposite bent portions of the member at their corresponding ends, said back being transversely grooved at its ends to receive said uniting members, the side walls forming said grooves affording stops for limiting the movement of said plate longitudinally of said bristle tufts.

In testimony whereof I have signed my name to this specification.

WILLIAM GREGORY KETT.
